9 Claims. (Cl. 260—680)

The present invention relates to a process for dehydrogenating aliphatic hydrocarbons of paraffinic and olefinic character and/or their partially halogenated derivatives, containing from 3 to 8 carbon atoms.

A primary object of our invention is to use halogen, more particularly chlorine, for the dehydrogenation of the said compounds in the gaseous phase.

A further object is to prepare hydrocarbons poorer in hydrogen from hydrocarbons richer in hydrogen or from halogenated hydrocarbons capable of conversion into hydrocarbons still richer in hydrogen under the reaction conditions than the end product desired.

A preferred object of our invention is to prepare diolefinic hydrocarbons from mono-olefinic and saturated hydrocarbons having the same number of carbon atoms.

It is well known that when saturated and unsaturated hydrocarbons react with chlorine, there may be various substitution reactions, or, in the case of unsaturated hydrocarbons, also addition reactions. Thus aliphatic hydrocarbons of the paraffin series may be reacted at elevated temperatures with halogen to form mono- and polyhalogenated hydrocarbons having the same length of carbon atoms. Olefinic hydrocarbons, when reacted with halogen at elevated temperatures, may form halogen substituted unsaturated hydrocarbons. In any of these cases the direct formation of dehydrogenation products by the elimination of hydrogen without halogen substitution has hitherto not been observed.

We have obtained in the treatment of aliphatic hydrocarbons and their partially halogenated derivatives with halogen at elevated temperatures considerable amounts of dehydrogenation products in addition to halogenated products formed by substitution. We have also found that by controlling the conditions we may increase the proportions of the dehydrogenation products.

Our process for the dehydrogenation of paraffinic and olefinic hydrocarbons having from 3 to 8 carbon atoms consists in thoroughly mixing the materials to be dehydrogenated with such an amount of halogen as is necessary for the formation of hydrogen halide with the hydrogen to be split off, causing the mixture to react at elevated temperature in the presence or absence of catalysts, cooling the reaction mixture as rapidly as possible, and isolating a fraction rich in dehydrogenation products.

Suitable materials for the process are normal and branched chain paraffins as for example bu-

5 tanes, pentanes, hexanes and octanes and the corresponding olefines, such as butylenes, amylenes, di-isobutylene, and the partially halogenated derivatives, especially those obtained as by-

products in the preparation of the dehydrogenation products. The starting materials may be used in a pure state, either as individual saturated and unsaturated compounds or in admixture with one another or with halogenated com-
10 pounds. The source of the compounds used is immaterial. The hydrocarbons may be derived from mineral oil or from natural or coke oven gas or from the hydrogenation of carbonaceous materials or from pyrolytic and cracking pro-

15 cesses. Furthermore such mixtures may be used in the form of hydrocarbon fractions consisting of hydrocarbons containing the same number of carbon atoms, as a butane-butylene cut, pentane-
15 amylene cut, etc. The olefines may as well be obtained by the dehydration of alcohols. Chlorine is the preferred halogen to be used in our process.

20 In carrying out the process according to our invention, it is especially important that the mixing of the material to be dehydrogenated with chlorine should be as thorough as possible. The mixing may if desired take place in the cold, for example by supplying the chlorine either through fine nozzles or porous stoneware bodies to the
25 hydrocarbons or partially chlorinated derivatives which are flowing at such a high velocity that the mixture proceeds in excess of the speed of flame propagation, as for example at a speed of 100 meters or more per second. After adding the

30 whole of the desired amount of chlorine, the resulting mixture is preferably led at the same high speed through tubes with inserted twisting bodies or rifling and thereby whirled through each other for the purpose of especially thorough
35 mixing. A specially thorough mixing may also be obtained for example in a tube in which the necessary irregularities in the gas flow are produced by alternate restrictions and widenings.

40 The injection of one body into the other may also be effected with a turbulent flow which produces an intimate mixing which enables the ingredients to become uniformly dispersed in each other. It is frequently preferable to use at the same time diluting gases or if hydrocarbons be used as the material to be dehydrogenated to lead them before the mixing through organic chlorine compounds, especially partially chlorinated hydrocarbons having the same number of carbon atoms and to saturate them therewith corre-

45 50 55 sponding to the vapor pressure.

One or more of the reactants may also be heated before or during the mixing; for example the hydrocarbons or chlorinated hydrocarbons may alone be heated and reacted when well mixed with the unheated chlorine, or on the other hand the chlorine may be heated, mixed with the non-preheated other initial material and reacted. Finally all the reactants may be heated before or during the mixing. The mixing of the gases may also take place in the reaction chamber itself, for example by blowing the preheated reactants into the reaction chamber through nozzles constructed like burners. It is also possible to introduce the heated initial mixture, separated into a plurality of partial streams, at different parts of the reaction vessel. Inert gases, as for example nitrogen, water vapor or carbon dioxide may also be added to the initial material or the mixture. In all cases, the mixing should be as thorough as possible.

The heating of the initial materials or their mixtures used according to this invention may be effected externally, as for example by leading them through hot tubes, or internally, as for example by leading in heated inert gases, as for example nitrogen or steam, such as are formed by burning hydrogen with oxygen. Electrical internal heating or eddy current heating may also be used. It is especially suitable to use the heat of reaction for preheating one or more of the reactants. The preheating is generally speaking carried to temperatures between about 100° and 500° C.

The mixture prepared in one of the said ways is supplied to the reaction chamber either cold or hot and led at a high velocity, so that it enters the place, at which the reaction proper is liberated by thermal action in empty vessels or by contact with heated filling bodies or catalysts, in excess of the speed of flame propagation. The initiation of the reaction is preferably effected by leading the gas mixture against a glowing body or against a flame. In order to avoid undesirable side-reactions, it may be preferable to ignite with a chlorine-detonating gas flame. The glowing body may be brought to the necessary temperature by direct heating or by an electric current. An inbuilt spark gap may also be used for ignition. Though catalysts or filler bodies may entirely be dispensed with, such substances may be used, especially when dehydrogenating mixtures containing chlorinated hydrocarbons. Among suitable catalysts there may be mentioned graphite, coke, pumice stone, silica gel, silicon carbide, activated oxides, ceramic masses of acid and basic nature, and also other known halogenation catalysts, such as the halides of copper, lead, nickel, tin, zinc, cadmium, bismuth, aluminium, magnesium, manganese, calcium, thorium, potassium, silicon or mixtures of the same. The said metal halides may also be applied to the said carrier substances.

The course of the reaction may be influenced to a great extent by using different pressures, as well as by using protecting gases or by varying the speed of flow. The reaction is preferably carried out in vessels in which the ratio of the surface to volume has been strongly displaced in favor of the surface. The reaction is especially favored by the graphite formed in the reaction vessel which is deposited as a coating on the walls and which renders the use of fillers unnecessary.

The optimum temperature for the dehydrogenation varies with different hydrocarbons and

with the amount of chlorine used, and also depends on the speed of flow at which the reactants are led through the reaction vessel. In general, the reaction temperature lies between 300° and 800° C., more particularly between 400 and 650° C. If the temperature is low, there is only a small proportion of dehydrogenation products formed, but pyrolysis and splitting of the carbon chain is completely avoided. If the temperature is high it becomes increasingly difficult to suppress the formation of compounds having less carbon atoms than the material to be dehydrogenated.

As already stated, the suitable reaction temperature also depends on the amount of chlorine used. The amount of chlorine to be used, in turn, depends on the amount of hydrogen to be split off. For example in the conversion of a saturated hydrocarbon into an olefine, the proportion of the latter to chlorine is selected at about 1:1. In the preparation of diolefines from saturated hydrocarbons, the ratio of hydrocarbons to chlorine of about 1:2 is chosen. If mixtures of olefines and diolefines are desired, appropriate intermediate ratios are chosen. In the conversion of an olefine into a diolefin, the ratio of olefine to chlorine is chosen at about 1:1. Since it is possible to work in a cycle, less than the theoretical amount of chlorine may be chosen. Generally speaking less than 0.3 molecular proportion and more than 2.2 molecular proportions of chlorine for each molecular proportion of the material to be dehydrogenated should not be used. If the amount of chlorine is too low, there is too small a proportion of dehydrogenation products formed, most of the chlorine being used for chlorination. On the other hand, if the amount of chlorine is too high, the formation of decomposition products such as vinyl chloride, methane and ethane, becomes more and more preponderant.

Within the above defined limits the reaction may be carried out depending on the nature of the products desired. When producing butadiene according to our invention, for example butane may be first reacted with less than the equimolecular proportion of chlorine. After having cooled off the reaction products and having removed the hydrogen chloride, the butylene formed may be separated off by causing it to react with chlorine to produce butylene chloride. This may be effected by treating the butylene, either in the pure state or in the presence of the other ingredients contained in the reaction products, at temperatures between about -30° and +100° C. with the necessary amount of chlorine. The butylene chloride may then be converted into butadiene by splitting off two molecules of hydrogen chloride according to one of the usual methods or preferably according to the process of our co-pending application Ser. No. 164,502, filed September 9, 1937.

Butane may also be reacted with an excess of chlorine, and butadiene be recovered from the reaction products for example by treating them with salts of heavy metals of the first and second group of the periodic system. The remaining mixture may either be recycled without further purification or be fractionated, the butylene being converted into butadiene by adding on chlorine and splitting off hydrogen chloride.

The reaction may also be carried out by supplying the amount of chlorine necessary for the formation of hydrogen chloride with the hydrogen to be split off to the materials to be dehydrogenated through suitable distributors and

mixing devices in two or more stages which are separated from each other by reaction zones.

This renders it possible to guide the process also on a technical scale by dosing of the amounts of chlorine and by regulating the temperatures before and in the single reaction stages. Each mixing should be carried out with the aid of efficient devices, as for example porous bodies, mixing nozzles or rifled tubes, so that the chlorine is dispersed as completely as possible within the shortest possible time. By adding the chlorine in stages, the reaction is subdivided and its whole course rendered milder. The temperatures in the different stages may be different; it is preferable to increase the reaction temperature from stage to stage in the direction of the passage of the gas. This offers the advantage that the temperatures can be accurately maintained because all intermediate stages of the chlorination and dechlorination are passed through comparatively slowly and the very great energy developed by the whole reaction is distributed more. For example half of the total amount of chlorine necessary may be mixed with the hydrocarbon at ordinary or elevated temperature or the mixture prepared in the cold may be heated. After this partial reaction, the residual chlorine is supplied through a suitable device in an extremely finely divided form, if necessary while cooling or heating.

Directly after leaving the reaction chamber, the reaction mixture should be cooled as rapidly as possible. This may be effected by direct or indirect cooling. For example water or other liquids, such as lye or oil, may be sprayed in. The chlorine compounds obtained in the process as by-products are especially suitable for quenching the gaseous reaction mixture. At the same time hydrogen chloride is split off therefrom thereby and an additional formation of olefines and diolefines is thus obtained.

The reaction mixture obtained, which contains a preponderating amount of olefines or diolefines and hydrogen chloride and chlorinated hydrocarbons of saturated and unsaturated nature in addition to small amounts of cleavage products, may be freed by cooling from the greater part of the chlorinated hydrocarbons obtained as by-products and then from the hydrogen chloride formed by washing or by distillation. Water or lye or diluted hydrochloric acid may be used for the washing. The last traces of hydrogen chloride may be bound in known manner with the aid of solid alkalies.

As already mentioned, the chlorinated hydrocarbons obtained as by-products, which have the same number of carbon atoms as the hydrocarbons used, may also in turn be converted into olefines or diolefines. If the desired olefine or diolefine is obtainable therefrom directly by splitting off hydrogen chloride, they are used for quenching the reaction mixture and thereby converted into olefines or diolefines. If, however, the introduction of further chlorine thereinto is necessary in order to obtain the desired unsaturated hydrocarbons, they are led, after admixing the necessary amount of chlorine, together with the mixture of hydrocarbon and chlorine into the reaction chamber again.

The reaction mixture freed from hydrogen chloride and the greater part of the chlorinated hydrocarbons formed and, if desired, after removal of the last traces of chlorine compounds, may be liquefied by cooling and compression and freed from small amounts of methane, acetylene,

hydrogen and, if desired, ethylene formed and purified by distillation. The separation of the diolefines from the olefines may also be effected in known manner, as for example by treatment with salts of heavy metals of the first and second groups of the periodic system.

The nature of this invention is further illustrated in the following examples, but the invention is not restricted to these examples.

Example 1

60 liters per hour of normal butane and 120 liters per hour of chlorine are led together after drying both gases and thoroughly mixed in a narrow bulb tube 50 centimeters long. The mixture is blown through a quartz tube 2 millimeters wide against a frontal plate heated externally to bright red heat and arranged in a quartz tube 15 millimeters wide. The resulting reaction mixture is led through a lateral attachment to the quartz tube into a cooling chamber and then through lye receivers and thus freed from hydrogen chloride formed. It is then split up into a condensable and an uncondensable fraction in a vessel cooled with carbon dioxide snow.

In this way 63 liters of condensable hydrocarbons are obtained from 116 liters of normal butane. These contain in all 94 per cent of olefines and diolefines of which 68 per cent is butadiene. There are also obtained 148 cubic centimeters of liquid chlorination products boiling for the most part between 60° and 70° and 110° and 120° C. and consisting of mono- and di-chlorobutane. The gas not condensed in the vessel cooled with carbon dioxide snow amounts to 20 liters. It contains 50 per cent of ethylene, 5 per cent of hydrogen and 18 per cent of methane.

40 The mixture consisting of butylene and butadiene is led through an acid solution of cuprous chloride kept at ordinary temperature. This solution is then heated to 60° C. whereby a gas containing about 96 per cent of butadiene is obtained. It may be polymerized in known manner.

45 The butylene, which has not been absorbed by the cuprous chloride solution, is admixed with an equimolecular amount of chlorine and led through a tube cooled with cold water. Dichlorbutane, having a boiling point of 117° C. is thus obtained. It is heated to about 300° C. and led with high velocity over a rod from silicon carbide electrically heated to bright red heat. The resulting mixture contains butadiene in a yield of 55 80 per cent.

Example 2

1 cubic meter per hour of normal butane is led through monochlorobutane having a boiling point of from 60° to 70° C., obtained as described in Example 1, heated to 50° C. and then mixed with 2 cubic meters per hour of chlorine and 200 liters of chlorine for each liter of vaporized monochlorobutane. (About 800 cubic centimeters of monochlorobutane are carried along each hour.) After thorough mixing in the manner described in Example 1, the gas mixture is led through a quartz tube 6 millimeters in internal width and blown against a frontal wall heated to bright red heat by direct heating with a chlorine-detonating gas flame which is situated in a quartz tube of 42 millimeters internal width. Directly behind the reaction zone, 200 cubic centimeters per hour of finely dispersed dichlorobutane having a boiling point of from 110° to 120° C., obtained as de-

scribed in Example 1, are sprayed in and the reaction product is further cooled by cooling, freed from hydrogen chloride by washing with lye and then condensed by cooling with carbon dioxide snow.

From 1 cubic meter of butane and 1 liter of mono- and di-chlorbutane there are obtained: 665 liters of condensable gases with 91.4 per cent by volume of total olefines and 64.1 per cent of butadiene, 200 liters of a gas containing, in addition to a few per cent of chlorine compounds and a little methane, acetylene and hydrogen, about 60 per cent by volume of ethylene, and 1.5 liters of liquid products which mainly boil at from 60° to 70° and from 110° to 130° C. and which consist of mono- and di-chlorbutane.

Example 3

50 liters per hour of normal butane are thoroughly mixed in the manner described in Example 1 with 100 liters per hour of chlorine and then led over 20 cubic centimeters of a catalyst consisting of an active aluminium oxide with 20 per cent of copper chloride at 350° C. After rapid cooling, the reaction mixture is led through a lye wash and thus freed from hydrogen chloride and condensed by cooling with carbon dioxide snow. From 50 liters of normal butane there are obtained: 33 liters of condensate with 84 per cent by volume of total olefines and 42 per cent of butadiene by volume, 62 cubic centimeters of liquid product mainly boiling between 60° and 70° C. and 12 liters of gas containing mainly ethylene in addition to a little acetylene, methane and hydrogen.

The following catalysts give similar results under the same conditions: active carbon, silicon tetrachloride on silica gel, the chlorides of aluminium, nickel, manganese, magnesium, zinc, tin, lead, bismuth, barium, cadmium and the oxychloride bismuth, all on active carbon as carrier mass.

Example 4

50 liters per hour of isobutane are mixed with 50 liters per hour of chlorine in the manner described in Example 1 and blown against a bright-glowing plate. After quenching, removing the hydrogen chloride and cooling with carbon dioxide snow, there are obtained 30 liters of condensate with 83 per cent by volume of total olefines and 67 per cent by volume of isobutylene. Moreover there are obtained 85 cubic centimeters of liquid product mainly boiling between 50° and 70° C. and 11 liters of gas containing 62 per cent of olefines in addition to a little acetylene, methane and hydrogen.

Example 5

110 liters per hour of normal butylene and 110 liters of chlorine are mixed at a great speed of flow in a mixing nozzle at ordinary temperature and led through a reaction tube consisting of silicon carbide which has a diameter of 5 millimeters and a length of 150 millimeters and which is filled with small pieces of silicon carbide. So much heat is developed by the initiated reaction that the reaction tube is kept at a weak red heat. By cooling the reaction gases to about 0° C. there are obtained 60 cubic centimeters of an oil and, by cooling in a carbon dioxide snow bath, a condensate the amount of which in the vaporized state is 71 liters. There are also obtained 14 liters of final gas which is not liquefied by cooling with the carbon dioxide snow.

The oil obtained at 0° C. has a specific gravity of 0.98. It boils to the extent of from 80 to 90 per cent between 60° and 80° C. and has an iodine value of 154. Accordingly it consists of mono-chlorhydrocarbons with 4 carbon atoms and to the extent of from about 55 to 60 per cent of unsaturated mono-chlorhydrocarbons. The condensate obtained by cooling in the carbon dioxide snow bath consists of 68 per cent of butadiene, 7 per cent of unsaturated chloro-hydrocarbons, in particular vinyl chloride, 21 per cent of unconverted butylene and 4 per cent of residual gas. There are thus obtained a yield of 48 per cent of butadiene, calculated on the initial material, and about 57.5 per cent of butadiene, calculated on the butylene converted.

The monochlor-hydrocarbons contained in the separated oil may be returned in circulation together with dichlorbutane and thus converted into butadiene.

Example 6

For the reaction, a vessel is used with consists of an empty chamotte tube into which projects a second, narrower chamotte tube. The inner tube is so arranged that the reaction gases led into the same must flow back through the outer tube.

Through a container with iso-pentane there is led at about 20° C. 0.5 cubic meter of nitrogen per hour, whereby 7.5 kilograms = 2.4 cubic meters of iso-pentane are vaporized per hour. This mixture of pentane and nitrogen is then thoroughly mixed with 3.6 cubic meters of chlorine. The proportion of pentane to chlorine thus amounts to 1:1.5 and therefore corresponds to the composition calculated for the preparation of a mixture of amylene and isoprene. The initial mixture is heated to initiate the reaction to a temperature of about 550° C. and led through the inner tube of the reaction vessel. The reaction takes place with strong evolution of heat in the outer chamber of the reaction vessel, the heat evolved being given up to the inner tube and serving there for heating the continuously flowing mixture of iso-pentane, nitrogen and chlorine. The reaction mixture is rapidly cooled to 30° C. and the hydrogen chloride formed washed out by treatment with water. By this cooling there are obtained at the same time 1.5 kilograms of a liquid which consists of saturated and unsaturated chloro-hydrocarbons, in particular chlorpentane. The gas mixture is further cooled to 20° below zero C., whereby 6.2 kilograms of a liquid are obtained which is vaporized and split up into diolefines and mono-olefines with the aid of an acid cuprous salt solution. In this way there are obtained 3.0 kilograms of diolefines, in particular isoprene, 2.2 kilograms of iso-amylene and 0.5 kilogram of unconverted iso-pentane. There is also obtained per hour 1 cubic meter of final gas consisting of 50 per cent of nitrogen, 40 per cent of olefines, in particular butylene, propylene and ethylene, and about 10 per cent of hydrogen and methane.

The iso-amylene and the chlorpentane may be returned in circulation for further splitting up to diolefines.

Example 7

10 cubic meters per hour of normal butane are mixed in a nozzle-shaped burner with 15 cubic meters per hour of chlorine which has been preheated in a tubular spiral to 400° C. This mixture is led at a speed of flow of 20

meters per second (calculated on the empty chamber) through a tube filled with lumps of coke and heated to 600° C. The gases at a temperature of about 600° C. leaving the reaction chamber are quenched with water, the hydrogen chloride formed thus being separated at the same time. There are also thus obtained 3.2 liters of liquid chloro-hydrocarbons the iodine value of which is about 70 and which consist mainly of chlorbutanes and chlorbutylenes. The gas mixture freed from hydrogen chloride is then cooled under a pressure of 15 atmospheres to 20° C., whereby the greater part is liquefied; there are also obtained about 1.5 cubic meters of final gas consisting to the extent of about 60 per cent of unsaturated hydrocarbons, in particular ethylene, and volatile chloro-hydrocarbons. By vaporizing the mixture liquefied under pressure there are obtained 8.2 cubic meters of a gas which consists of 94 per cent of unsaturated compounds, namely 45 per cent of butadiene, 12 per cent of unsaturated chloro-hydrocarbons, in particular vinyl chloride, and 37 per cent of butylene, and about 6 per cent of unconverted butane. Moreover there remains a non-vaporized portion of 0.5 liter consisting of chlorbutanes and chlorbutylenes. The yield of butadiene amounts to 36.9 per cent and that of normal butylene to 30.3 per cent, calculated on the normal butane introduced, by a single passage. The normal butylene and the chloro-hydrocarbons may, if desired, be supplied again to the reaction, whereby the total yield of butadiene may be considerably increased.

Example 8

10 cubic meters of butylene heated to 300° C. are thoroughly mixed with 10 cubic meters of chlorine heated to 350° C. and the mixture is led through an empty tube at a speed of flow of 40 meters per second. For the reaction a vessel is used consisting of an empty chamotte tube into which projects a second, narrower chamotte tube. The inner tube is arranged so that the reaction gases led therethrough must flow back through the outer tube. In the outer of the chambers formed by the two concentric tubes, the reaction between the butylene and the chlorine takes place, temperatures of from about 650° to 700° C. being attained. A part of the heat of reaction is given up to the inner tube, whereby the initial gas led through the inner tube is preheated. The residual heat of reaction is carried away by the reaction gas and removed by spraying water into the same, whereby the hydrogen chloride formed is removed at the same time. For further purification, the gas is led over lime, then cooled to about 80° below zero C. without the use of pressure whereby the greater part of the gas is liquefied. There remain 1.2 cubic meters of final gas containing 70 per cent of olefines, mainly butylene. If the condensate obtained by cooling to 80° below zero C. be vaporized at room temperature, there are obtained 9.1 cubic meters of a gas mixture consisting of 97 per cent of mono- and di-olefines of which about 82 per cent is butadiene. There also remains a non-vaporized portion of about 1.2 liters, consisting mainly of chlorbutylenes. The butadiene is separated by distillation from the butylene and the latter is returned in circulation. The yield of butadiene is 74.6 per cent by a single passage. By returning the butylene, the yield of butadiene becomes even higher.

Example 9

As a reaction vessel, use is made of a stoneware tube in which is arranged concentrically a porous stoneware candle. Active carbon is arranged between the two tubes as a catalyst. 5 2 cubic meters of normal butane and 2 cubic meters of normal butylene per hour are led at a speed of flow of 10 meters per second (calculated cold) through the stoneware tube which is kept at a temperature of about 550° C. by returning the hot reaction gases along the outer wall. 6 cubic meters per hour of chlorine are mixed with the hydrocarbon mixture through the porous stoneware candle arranged in the interior. The gas mixture leaving the reaction chamber is immediately quenched by cooling with water, freed from hydrogen chloride by washing with lye and fractionally condensed by leading into a cooled vessel.

10 15 20 By reaction for one hour, the following products are obtained:

25 1.8 liters of liquid olefinic chloro-hydrocarbons having a boiling point mainly between 70° and 80° and 120° and 130° C. obtained by water-cooling,
30 3.15 cubic meters of gas condensable in a bath of carbon dioxide snow and containing 96 per cent of total olefines of which 84 per cent is butadiene, and 0.6 cubic meter of final gas containing 52 per cent of ethylene.

Example 10

35 A porous stoneware candle is arranged concentrically within a stoneware tube which is heated to 150° C. In this apparatus, 5 cubic meters per hour of normal butane are mixed at a speed of flow of 10 meters per second (measured cold) with 5 cubic meters per hour of chlorine which is introduced through the porous candle. Reaction takes place between the butane and the chlorine; this proceeds at 500° C. and yields butylene and hydrogen chloride as well as chlorbutanes. The reaction gas of the first stage is then mixed in a chamber heated to 550° C. with a further 5 cubic meters per hour of chlorine which is introduced through a second concentrically arranged mixing candle. The temperature of the second chamber maintains itself without additional heating after a short initiation time. The reaction gas leaving this chamber is quenched by indirect water-cooling, freed from hydrogen chloride by washing with lye and split up into its single components by leading into a cooling vessel.

40 45 50 55 In this way the following substances are obtained from 10 cubic meters of normal butane:

60 6.8 cubic meters of gas condensable in a bath of carbon dioxide snow containing 70 per cent of total olefines of which 54 per cent is butadiene; 0.9 cubic meter of final gas containing 62 per cent of ethylene; and 9.4 liters of liquid products boiling at from 70° to 80° and from 100° to 130° C. consisting mainly of olefinic chloro-hydrocarbons.

65 What we claim is:

70 75 1. The process of dehydrogenating butane which consists in causing a mixture of butane with chlorine, containing at least 0.3 and at most about 2.2 molecular proportions of chlorine for one molecular proportion of butane, to react in the gas phase at temperatures between 300° and 800° C., the time of heating and the temperature being so chosen as to avoid substantial formation of compounds having less carbon atoms than the hydrocarbon to be dehydrogenated, quenching the gaseous reaction mixture to about

ordinary temperature by contacting it with partially chlorinated aliphatic hydrocarbons containing 4 carbon atoms, removing the hydrogen chloride by contacting the gaseous reaction mixture with a solvent for hydrogen chloride, and separating the unsaturated hydrocarbons obtained from co-present material.

2. The process of dehydrogenating butane which consists in causing a mixture of butane with at most 1 and at least 0.3 molecular proportion of chlorine to react at temperatures between 300° and 800° C., the time of heating and the temperature being so chosen as to avoid substantial formation of compounds having less carbon atoms than the hydrocarbon to be dehydrogenated, cooling off the reaction mixture substantially below reaction temperature, removing the hydrogen chloride by contacting the reaction mixture with a solvent for hydrogen chloride, treating the remaining material with chlorine at temperatures below 100° C. and fractionating the reaction mixture formed to obtain therefrom a fraction rich in butylene chloride.

3. The process of dehydrogenating butane which consists in causing a mixture of butane with at most 1 and at least 0.3 molecular proportion of chlorine to react at temperatures between 300° and 800° C., the time of heating and the temperature being so chosen as to avoid substantial formation of compounds having less carbon atoms than the hydrocarbon to be dehydrogenated, cooling off the reaction mixture substantially below reaction temperature, removing the hydrogen chloride by contacting the reaction mixture with a solvent for hydrogen chloride, treating the remaining material with chlorine at temperatures below 100° C., fractionating the reaction mixture formed to obtain therefrom a fraction rich in butylene chloride, contacting this fraction with a glowing electrically heated body and separating butadiene from the materials co-present.

4. The process of dehydrogenating compounds of the class consisting of aliphatic hydrocarbons of the paraffin and mono-olefine series containing 3-5 carbon atoms and their partially halogenated derivatives which consists in causing a mixture of the material to be dehydrogenated and chlorine, containing at least 0.3 and at most 2.2 molecular proportions of chlorine for one molecular proportion of the material to be dehydrogenated, to react in the gas phase at temperatures between 300 and 800° C., the time of heating and the temperature being so chosen as to avoid substantial formation of compounds containing less carbon atoms than the compound to be dehydrogenated, quenching the gaseous reaction mixture to about ordinary temperature by contacting it with partially chlorinated aliphatic hydrocarbons containing substantially the same number of carbon atoms as the material to be dehydrogenated, removing the hydrogen chloride by contacting the gaseous reaction mixture with a solvent for hydrogen chloride and separating the unsaturated hydrocarbons obtained from co-present material.

5. The process of dehydrogenating compounds of the class consisting of aliphatic hydrocarbons of the paraffin and mono-olefine series containing 3-5 carbon atoms and their partially halogenated derivatives which consists in causing a mixture of material to be dehydrogenated and chlorine, containing at least 0.3 and at most 2.2 molecular proportions of chlorine for one molecular proportion of the material to be dehydro-

genated, to react in the gas phase at temperatures between 300 and 800° C., the time of heating and the temperature being so chosen as to avoid substantial formation of compounds containing less carbon atoms than the compound to be dehydrogenated, cooling off the reaction mixture substantially below reaction temperature, removing the hydrogen chloride formed by contacting the reaction mixture with a solvent for hydrogen chloride, treating the remaining material with chlorine at temperatures below 100° C. and fractionating the reaction mixture formed to obtain therefrom a fraction rich in olefine chlorides.

15 6. The process of dehydrogenating compounds of the class consisting of aliphatic hydrocarbons of the paraffin and mono-olefine series containing 3-5 carbon atoms and their partially halogenated derivatives which consists in causing a mixture of material to be dehydrogenated and chlorine, containing at least 0.3 and at most 2.2 molecular proportions of chlorine for one molecular proportion of the material to be dehydrogenated, to react in the gas phase at temperatures between 300 and 800° C., the time of heating and the temperature being so chosen as to avoid substantial formation of compounds containing less carbon atoms than the compound to be dehydrogenated, cooling off the reaction mixture substantially below reaction temperature, removing the hydrogen chloride formed by contacting the reaction mixture with a solvent for hydrogen chloride, treating the remaining material with chlorine at temperatures below 100° C. and fractionating the reaction mixture formed to obtain therefrom a fraction rich in olefine chlorides, contacting this fraction with a glowing electrically heated body and separating diolefines from the materials co-present.

20 7. The process of dehydrogenating partially halogenated aliphatic hydrocarbons containing 3-5 carbon atoms in the molecule which consists in causing a mixture of the material to be dehydrogenated and chlorine, containing at least 0.3 and at most 2.2 molecular proportions of chlorine for one molecular proportion of the material to be dehydrogenated, to react in the gas phase at temperatures between 300 and 800° C., the time of heating and the temperature being so chosen as to avoid substantial formation of compounds containing less carbon atoms than the compound to be dehydrogenated, quenching the gaseous reaction mixture to about ordinary temperature by contacting it with partially chlorinated aliphatic hydrocarbons containing substantially the same number of carbon atoms as the material to be dehydrogenated, removing the hydrogen chloride by contacting the gaseous reaction mixture with a solvent for hydrogen chloride and separating the unsaturated hydrocarbons obtained from co-present material.

25 8. The process of dehydrogenating partially halogenated aliphatic hydrocarbons containing 3-5 carbon atoms in the molecule which consists in causing a mixture of material to be dehydrogenated and chlorine, containing at least 0.3 and at most 2.2 molecular proportions of chlorine for one molecular proportion of the material to be dehydrogenated, to react in the gas phase at temperatures between 300 and 800° C., the time of heating and the temperature being so chosen as to avoid substantial formation of compounds containing less carbon atoms than the compound to be dehydrogenated, cooling off the reaction mixture substantially below reaction tempera-

ture, removing the hydrogen chloride formed by contacting the reaction mixture with a solvent for hydrogen chloride, treating the remaining material with chlorine at temperatures below 100° C. and fractionating the reaction mixture formed to obtain therefrom a fraction rich in olefine chlorides.

9. The process of dehydrogenating partially halogenated aliphatic hydrocarbons containing 3-5 carbon atoms in the molecule which consists in causing a mixture of material to be dehydrogenated and chlorine, containing at least 0.3 and at most 2.2 molecular proportions of chlorine for one molecular proportion of the material to be dehydrogenated, to react in the gas phase at temperatures between 300 and 800° C., the time

5 of heating and the temperature being so chosen as to avoid substantial formation of compounds containing less carbon atoms than the compound to be dehydrogenated, cooling off the reaction mixture substantially below reaction temperature, removing the hydrogen chloride formed by contacting the reaction mixture with a solvent for hydrogen chloride, treating the remaining material with chlorine at temperatures below 10 100° C. and fractionating the reaction mixture formed to obtain therefrom a fraction rich in olefine chlorides, contacting this fraction with a glowing electrically heated body and separating diolefines from the materials co-present.
